CLAIM

The ornamental design for a hand-held radar, as shown and described.

DESCRIPTION

FIG. 1 is a perspective view of a hand-held radar, showing my new design;

FIG. 2 is a right side elevational view thereof, the left side being a mirror image thereof;

FIG. 3 is a bottom plan view thereof;

FIG. 4 is a rear elevational view thereof;

FIG. 5 is a front elevational view thereof;

FIG. 6 is a top plan view thereof; and,

FIG. 7 is a perspective view from the rear, bottom and right side thereof.

Fig.1.**Fig.2.****Fig.3.****Fig. 4.****Fig. 5.****Fig. 6.****Fig.7.**
